UNITED STATES PATENT OFFICE.

RAYMOND ENGELMAN MACDONOUGH, OF MINNEAPOLIS, MINNESOTA.

FILLER-CUP AND CLOSURE FOR PRESSURE-TANKS.

1,397,320.

Specification of Letters Patent. Patented Nov. 15, 1921.

Application filed June 21, 1920. Serial No. 390,328.

To all whom it may concern:

Be it known that I, RAYMOND ENGELMAN MACDONOUGH, a citizen of the United States, residing at Minneapolis, in the county of 5 Hennepin and State of Minnesota, have invented a new and useful Filler-Cup and Closure for Pressure-Tanks, of which the following is a specification.

My invention relates to improvements in 10 filler-cups and closures for pressure tanks.

Its object is to provide a simple, durable, compact and inexpensive device of this kind, particularly, though not exclusively for sprayers, adapted to allow ready access to 15 a tank and permit the convenient charging and sealing thereof.

A further object is to supply a device of 20 this kind, provided with means adapted to coöperate with pump mechanism, whereby a mounting for the pump is furnished, means for actuating the removable sealing member 25 of the device is supplied and means for conveniently carrying the tank is provided.

With the foregoing and other objects in 30 view, which will appear in the following description, the invention resides in the novel combination and arrangement of parts and in the details of construction herein-after described and claimed.

35 In the drawings, Figure 1 is a central sectional view illustrating a device embodying my invention, the pressure tank and pumping mechanism being illustrated only in part; Fig. 2 is a central sectional view in detail of the filler-cup, said section being taken at right angles to view shown in Fig. 1; Fig. 3 is a sectional view taken on the line 3—3 of Fig. 1 and shows the filler-cup and sealing cap in plan; Fig. 4 is an elevation of the sealing cap and Fig. 5 is a sectional view in detail taken on the line 5—5 of Fig. 4, the lugs on the pump plunger, being illustrated in opposed operative relation.

45 Referring to the accompanying drawings, I have used the reference numeral 10 to indicate the top of an upright pressure tank, 11 to designate a pump barrel and 12 a plunger rod therein. The barrel 11 has an external annular flange 13 at its upper end and the rod 12 is supplied with opposed lugs 14 and a handle 15 by means of which the rod 12 is reciprocated and turned and the tank carried.

50 A filler-cup A, suitably fitted in the top 10 of the pressure tank, comprises a cup-like

casting 16 having an opening 17 in the bottom thereof and an annular supporting shoulder 18 at the upper margin of said opening. Segmental flanges 19 on the inner 60 periphery of the filler-cup and above the shoulder 18 are formed to provide cam surfaces 20 on the under sides thereof. A gasket 21, or other suitable sealing element, is placed upon the shoulder 18 to receive the 65 thrust of a removable sealing cap B. This cap includes a disk-like body 21 having peripheral segmental flanges 22 adapted to fit between the ends of flanges 19 on the cup A and pass beneath said flanges, when the 70 cap is turned. The upper sides of the flanges 22 are formed to provide cam surfaces 23 adapted, upon a slight turn of the cap, to coact with the cam surfaces 20 of the flanges 19 on the cup and seat and lock the cap B 75 securely against the sealing element in the bottom of the cup. A head 24 with angular sides provides for turning the cap B to secure the same within the cup or release it therefrom. It will be noted here that the 80 cup provides a receptacle for fluids introduced to the tank, thus eliminating the necessity of the use of a funnel; that the relatively large opening at the bottom of the cup provides for quickly filling a tank 85 and that the cap B, when seated, is substantially contained within the confines of the cup.

My device is particularly adaptable to center pump sprayers and the like. The 90 opening 17 in the cup A receives the barrel 11 of the pump mechanism and the flange 13 on said barrel rests upon the gasket 21. The cap B is formed with a bore 25 to receive the plunger rod 12 and the head 24 on said 95 cap is cored out as shown in Figs. 1 and 5, radial abutments 26 being stationed in opposed relation and a key-way 27 being formed in the upper side of said head. The engagement of the cap B against the barrel 100 11 holds the latter in place. Upon the insertion of the lugs 14, through the key-way 27 and a slight turn of the handle 15 in either direction, said lugs are held against removal from the head 24 and serve as 105 hang-ers, in the event that it should be desired to carry the tank by the handle 15. A further turn of the handle impinges the lugs 14 against the abutments 26 within the head 24 and results in seating the cap, when the 110 direction of rotation is to the right. When the direction of rotation is to the left, the

impingement of the lugs 14 against the abutments 26 results in releasing the cap B from the flanges 19 on the cup, said cap being thereafter readily removed from the cup, by 5 lifting upon the handle 15.

My improved device is particularly advantageous because of its simplicity, compactness, cheapness of manufacture, and its various desirable features in the use thereof.

10 Changes in the specific form of my invention, as herein disclosed, may be made within the scope of what is claimed without departing from the spirit of my invention.

Having described my invention, what I 15 claim as new and desire to protect by Letters Patent is:

1. The combination with an externally flanged barrel and plunger therefor having opposed lugs thereon, of a filler-cup having 20 an opening in the bottom thereof to removably receive said barrel, an annular shoulder at the margin of said opening, internal segmental flanges within the filler-cup above said shoulder, a gasket resting upon the 25 shoulder and adapted to receive the flange on the barrel, a removable cap, segmental flanges on said cap arranged to engage beneath the flanges of the cup and coöperate therewith to firmly secure the cap in holding 30 position against the cylinder, said cap having a bore therein to slidably and revolvably receive the plunger, a hollow head on said

cap, formed with a key-way in the top thereof to receive the lugs on the plunger and radial abutments within the head designed to 35 be engaged by said lugs upon turning movements of the plunger, whereby the cap is turned and released from the cup or fixed in clamped relation with respect thereto.

2. In a device of the class described, the 40 combination with a barrel and plunger therefor, of a filler-cup adapted to removably receive said barrel, a cap removable from said filler-cup, coöoperating members on said cap and filler-cup arranged so that 45 when the cap is turned through a partial revolution in one direction it may be removed from the filler-cup and when turned through a partial revolution in the reverse direction it is clamped in holding position 50 against the barrel wherein the connection between said barrel and filler-cup is made pressure proof, said cap having a bore therein to slidably and revolvably receive the plunger and members on said cap and plunger designed to be moved into and out of coöperative relation, said members in coöperative relation being adapted to result in the turning of the cap when the plunger is turned. 55

60 In testimony whereof, I have signed my name to this specification.

RAYMOND ENGELMAN MACDONOUGH.
